UNITED STATES PATENT OFFICE.

MATTHEW J. BOGERT, OF DEMAREST, NEW JERSEY.

DESIGN FOR A BOX.

SPECIFICATION forming part of Design No. 20,167, dated September 23, 1890.

Application filed June 5, 1890. Serial No. 354,396. Term of patent 7 years.

To all whom it may concern:

Be it known that I, MATTHEW J. BOGERT, a citizen of the United States, residing at Demarest, in the county of Bergen and State 5 of New Jersey, have invented and produced a new and original Design for a Box; and I do hereby declare the following to be a full, clear, and exact description of the same, reference being had to the accompanying drawings, 10 forming a part thereof.

This invention has relation to a design for a box; and it consists in the novel arrangement of parts, as hereinafter more fully described, illustrated in the accompanying drawings, and pointed out in the appended claim.

The object of my invention is to provide an ornamental box in the shape of a vase and provide it with a top or lid.

In the drawings, Figure 1 is a side view of 20 a box illustrating my design. Fig. 2 is a vertical section of the same.

Referring to the accompanying drawings, in which like letters of reference indicate corresponding parts in both figures, the letter 25 A designates the body of the box, which rep-

resents a vase the exterior wall *a* and the vase *a'* of which are on an ogee curve, terminating at the upper edge of the vase in an annular lip *B*. The interior of the vase is vertical, as shown, and at the junction of the 30 said wall at its upper edge with the lip *B*, a shoulder *C* is formed. The top *D*, as plainly shown in Fig. 2, is cylindrical and provided at its lower edge and outer wall with a shoulder *d*, which bears against the inner edge of 35 the lip *B* and top of shoulder *C*, and, as will be noticed, the interior diameter of the lid is the same as the interior diameter of the vase.

Having thus fully described my invention, what I claim as new, and desire to secure by 40 Letters Patent, is—

A design for a box or vase, as herein shown and described.

In testimony whereof I affix my signature in presence of two witnesses.

MATT. J. BOGERT.
